ABSTRACT

A visual information apparatus comprising a housing and a panel on which appear the insignia formed in the housing. A screen divided into squares is fitted over the panels and the insignia may be sighted on the screen.

VISUAL INFORMATION APPARATUS

The present invention relates to visual information apparatus.

In accordance with the invention, a device which provides indicia on one panel thereof which may be provided with a screen cover divided into squares through which the various indicia appearing on said panel can be viewed to better advantage.

The invention will be made apparent from the following description and the accompanying drawings in which:

FIG. 1 is a perspective view of the device without the screen;

FIG. 2 is the screen cover and

FIG. 3 is the device with the screen cover secured thereon.

Referring now to the drawings in detail the device includes a housing 1, provided with a panel 2 divided into vertical sections 5. The indicia 6, appear on the panel 2. A rectangular cover 3, shown in FIG. 2, is divided into squares 4 and is secured over the offset panel 2.

It will be noted from FIG. 1 that the indicia appearing on the panel 2 is in the form of a series of dots all arranged along the vertical lines which divide the panel 2 into the vertical sections 5. In the particular example illustrated the left series of dots in FIG. 1 indicate the number 1 while the right series of dots indicate the number 2. Actually the series of dots which form the number 1 take the form of an outer and inner series of dots both of which form the numeral 1 with a space between the outer and inner series conforming to the width of each vertical section 5. The same is true of the number 2 which is formed by an outer and inner series of dots all arranged along the vertical lines which divide the panel into the vertical sections 5.

When viewing the bare panel 2, as it appears in FIG. 1, the fact that the series of dots form the numbers 1 and 2 is not immediately apparent because of the presence of the vertical lines dividing the panel 2 into the vertical sections 5. However, when the panel is covered by the cover 3 having the screen divided at its mesh into the squares 4 which are smaller in their dimensions than the width of a section 5, the viewer is

not aware of the presence of the vertical lines which form the section 5 and along which the dots are arranged. The screen 4 forms a background and the viewer is not even aware of the meshes of the screen.

5 All that the viewer sees are the dots 6 which are readily apparent through the screen 4 so as to make the pattern along which the dots 6 are arranged far more readily apparent to the observer than when the panel 2 is uncovered, so that by way of the cover 3 it is possible for 10 the observer to immediately appreciate what indicia are formed by the pattern of dots. Thus it is possible to view the indicia through the screen to better advantage than without the screen cover. The effect of the screen cover is to make the vertical lines disappear when the 15 entire assembly is observed so that the dots which form the indicia stand out very clearly. It will be noted that where the dots are arranged along vertical lines the distance between the dots on any one vertical line is equal to the distance between a pair of lines or in other words to the width of a vertical section 5.

20 The embodiment of the invention in which an exclusive privilege is claimed is as follows:

1. A visual information apparatus comprising a panel having vertical lines dividing the panel into vertical sections of uniform width, a plurality of dots arranged on said lines and forming indicia on said panel, and a screen cover covering said panel for rendering the indicia formed by said dots more clearly apparent, said screen cover having a mesh of open squares the dimensions of each of which are substantially smaller than the width of each vertical section of said panel.

25 2. The combination of claim 1 and wherein the dots are arranged according to a predetermined pattern having outer and inner rows of dots for each indicium.

30 3. The combination of claim 2 and wherein the outer and inner rows of dots are spaced from each other by a distance equal to the width of each vertical section.

35 4. The combination of claim 3 and wherein the dots are arranged only on said vertical lines with rows of dots which extend along any one line being spaced apart from each other by a distance equal to the width of each vertical section.
